UNITED STATES PATENT OFFICE.

HENRY K. SANDELL, OF CHICAGO, ILLINOIS, ASSIGNOR TO HERBERT S. MILLS, OF CHICAGO, ILLINOIS.

TONE-ARM CONSTRUCTION.

1,376,042.

Specification of Letters Patent. Patented Apr. 26, 1921.

Application filed June 19, 1920. Serial No. 390,210.

To all whom it may concern:

Be it known that I, HENRY K. SANDELL, a citizen of the United States, residing at 221 So. Green street, Chicago, in the county of 5 Cook and State of Illinois, have invented a new and useful Improvement in Tone-Arm Constructions, of which the following is a specification.

The present invention relates to improvements in tone arm construction, and more particularly to the construction of jointed tone arms by means of which a single sound box may be adapted for use with either the lateral wave or the hill-and-dale wave type 15 of sound record. It will be fully understood from the following description of a specific embodiment thereof, which is illustrated in the accompanying drawings, in which:

20 Figure 1 is a plan view of a tone arm embodying the present invention;

Fig. 2 is a plan view through the tone arm, partially broken away, in which the section thereof attached to the sound box 25 is illustrated in a different position from that illustrated in Fig. 1;

Fig. 3 is a side elevation of the tone arm, partially broken away, in the same position as shown in Fig. 1;

30 Fig. 4 is a longitudinal sectional view through the tone arm on the line 4 of Fig. 1, and

Fig. 5 is a sectional view through the sound box on the lines 5 of Figs. 1 and 3.

35 Referring more particularly to the drawings, the numeral 10 indicates a tone arm section, preferably tapering in form, by which the sound waves from the sound box are conveyed to the amplifier and which is 40 mounted for a limited pivotal or lateral movement in the customary manner (not shown). At its end this tone arm section is provided with a circular flange 11, which is angularly disposed with reference to the 45 axis of the tone arm section 10. In the specific device illustrated in the drawing, the plane of the circular terminal flange 11 is at an angle of about 55 to 57 degrees to the axis of the conduit section 10.

50 A second conduit section 12, to which the sound box 13 is attached, is secured to the tone arm section so as to be movable relatively thereto in the following manner. The end by which said conduit section 12 is attached to the tone arm section 10 is likewise

provided with a circular flange 14, which has substantially the same radius as the circular flange 11, and which mates with the latter when the tone arm section 12 is positioned in axial prolongation of the tone arm section 10 as illustrated in Fig. 1 and in section in Fig. 4. The circular flanges 11 and 14 are secured in mating relationship with each other by means of two resilient clamping members 15, 15. These members fit over 60 or straddle the edges of the mated flanges, and are secured, preferably by screws 16, 16, to the flange 11. The portion of these clamps 15, 15 in contact with the flange 14 are provided with resilient or spring extensions 17, 17, which lie against the surface of the flange 14 and hold it securely against the flange 11. It is thus apparent that the flange 14 may be rotated relatively to the flange 11, while being maintained in 70 mating relationship therewith. Two stops 18 and 19 are provided on the flange 14, which, by engagement with the clamp 15, 15, determine the limits of movement of the flange 14 relative to the flange 11. 80

The tone arm section 12, carrying the sound box 13, rotates with the flange 14. In one position of the tone arm section 12, determined by engagement of stop 18 with one of clamps 15, the tone arm section 12 85 forms an axial prolongation of the tone arm section 10. This position of the elements is shown in Figs. 1, 3 and 4, and with the type of sound box illustrated, which is specifically described in my copending application Serial No. 309,209 filed June 19, 1920, the lateral wave type of records may be played. With this type of sound box it may be noted that in this position the diaphragm is at an acute angle to the plane of the record, as is clearly indicated in Figs. 3 and 4, and the stylus holder extends from a point at the side of the sound box at right angles to the plane of the diaphragm. On rotating the tone arm section 12 with the flange 14 upon 100 the flange 11 until the stop 19 engages the other clamping member 15, the relative positions indicated in Fig. 2 are assumed by the parts, the plane of the diaphragm now being perpendicular to the plane of the record. In 105 this position the stylus holder assumes substantially the same position relative to the longitudinal axis of the tone arm section 10 as in its former position, illustrated in Fig. 1.

Although the present invention has been 110

described in connection with the specific details of a device embodying it, it is not intended that these details shall be regarded as limitations upon the scope of the invention, except in so far as included in the accompanying claims.

I claim:

1. A tone arm comprising a relatively fixed tapered conduit section, a circular flange secured to its end at an angle to its longitudinal axis, a second conduit section having a taper conforming to that of the fixed conduit section, a circular flange secured to the end of said second section, said flange mating with the first mentioned circular flange, and means for retaining said flanges in mating relationship while permitting relative movement of the second flange with respect to the first flange.
2. A tone arm comprising relatively fixed and movable sections, mating circular flanges terminating said sections, clamps securing said flanges to each other, said clamps comprising members straddling the edges of the mating flanges and being secured at one side to the flange on the fixed section and resiliently engaging on the other side the flange on the movable section, whereby relative movement of the second mentioned flange with respect to the first mentioned flange is permitted.
3. A tone arm comprising relatively fixed and relatively movable sections, mating circular flanges terminating said sections,

clamps securing said flanges to each other, 35 said clamps comprising members straddling the edges of the mating flanges and being secured at one side to the flange on the fixed section and resiliently engaging on the other side the flange on the movable section, whereby 40 relative movement of the second mentioned flange with respect to the first mentioned flange is permitted and stops on said movable flange to engage said clamps and limit the relative movements of the movable 45 flange with respect to the fixed flange.

4. A tone arm comprising a relatively fixed conduit section, a circular flange secured to its end at an angle of 55 to 57° to its longitudinal axis, a second conduit section, 50 a circular flange secured to the end of second conduit section, said flange mating with the first mentioned circular flange, means for retaining said flanges in mating relationship while permitting relative movement of the 55 second flange with respect to the first flange, a sound box secured to the opposite end of the second section, said sound box having a stylus holder arranged laterally thereof and projecting at right angles to the plane of the 60 diaphragm of the sound box, whereby on turning the second section relative to the first mentioned tone arm section, the sound box assumes a new position while the stylus holder retains its relative position with respect to the axis of the fixed tone arm section.

HENRY K. SANDELL.
